PRESS FOR FORMING TABLETS AND THE LIKE

Albert S. Kux, Chicago, Ill.

Application October 3, 1940, Serial No. 359,581

11 Claims. (Cl. 18—16)

This invention relates to improvements in presses particularly adapted though not necessarily limited in use for forming tablets from granular or powdered material, and one of the objects of the invention is to provide in a press of this character improved means whereby a tablet of this character may be formed with bosses or projections on opposite sides thereof, and improved means whereby the material may be manipulated or handled, and the tablet or work being formed will be held under pressure during a pause or dwell in the mechanism, thereby allowing the material to flow or set, thus insuring uniform density.

A further object is to provide in a machine of this character improved means whereby an oversupply of material will be delivered to the compression chamber or pocket between the compression plungers to insure the proper amount of material in each tablet, and which oversupply will be returned to the source of supply before the compressing operation starts.

A further object is to provide in a press of this character improved means whereby the material in the pocket may be displaced or distributed before the compressing operation so as to position some of the material to provide for the formation of projections on opposite sides of the body of the article being produced.

A further object is to provide improved means whereby an extra squeeze or compression will be imparted to the tablet or work after the compression plungers have reached the limit of their initial compressing or squeezing operation.

A further object is to provide in a press of this character a plurality of different means, each operable separately and successively upon the compression plungers to impart independent movements thereto all during one cycle of operation of the press.

A further object is to provide in a machine of this character improved means whereby tablets which are provided with countersinks or projections on opposite sides thereof may be readily ejected from the machine.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a front elevation of a machine of

this character constructed in accordance with the principles of this invention.

Figure 2 is a side elevation of Figure 1, on an enlarged scale, and the upper part of the machine broken away.

Figure 2A is an enlarged detail side elevation of the upper portion of the machine which is broken away from Figure 2.

Figure 3 is a detail horizontal sectional view taken on line 3—3 Figure 2.

Figure 4 is a detail horizontal view taken on line 4—4 Figure 2.

Figure 5 is an irregular vertical sectional view taken on line 5—5 Figure 4.

Figure 6 is an enlarged detail sectional view taken on line 6—6 Figure 1.

Figure 7 is an enlarged detail sectional view taken on line 7—7 Figure 1.

Figure 8 is a detail sectional view similar to Figure 7 of the compression chamber and lower compression members showing the parts in a different position from that shown in Figure 7.

Figure 9 is a view similar to Figure 7 showing the parts in their final compressing position.

Figure 10 is a detail view partly in front elevation, partly in section, and with parts broken away of a modified form of the invention, showing the manner in which core members may be actuated.

Figure 11 is a view of another modified form of the invention partly in elevation, partly in section and with parts omitted, showing the manner in which an additional "squeeze" may be given to one of the upper compression members after the upper compression member has reached the limit of its initial compressing movement.

Referring more particularly to the drawings, the numeral 15 designates a supporting frame or structure which may be of any desired size and configuration and rests upon a base 16. Intermediate the top and bottom of the frame is a supporting ledge or platform 17 formed integral with the frame and below this support are spaced uprights 18 in which a slide 19 is adapted to reciprocate. The sides of the slide are preferably tapered, as at 20, and move in suitable guideways 21, being held against displacement by suitable gibs 22.

Supported by the slide in any suitable manner are a plurality of adjustable abutments 23—24—25 which are preferably in the form of screws arranged in alignment and adapted to be vertically adjusted with respect to the slide, being held in their adjusted position in any desired or suitable

manner, such as by means of clamp screws or bolts 26.

This slide together with the abutments 25 is adapted to be moved in one direction preferably by gravity, although if desired any suitable spring may be provided to accomplish that end.

The slide is adapted to be moved in the opposite direction by means of a plurality of levers 27-28-29 (see particularly Figure 5). The levers are respectively pivotally supported intermediate their ends as at 30-31-32, and the levers are spaced one above the other. The forward ends 33-34-35 of the respective levers 27-28-29 are disposed below and in alignment with the respective abutments 23-25-24 and each is respectively adapted to engage its abutment at predetermined times in the cycle of operation in the press to raise the slide 19.

To that end there is provided a cam shaft 36 which has mounted thereupon and for rotation therewith a series of cams individual to the levers 27-28-29. A cam 37 carried by the shaft 36 is adapted to contact the end 38 of the lever 27 and if desired a roller may be carried by the lever to be engaged by the cam. A cam 39 is also carried by the shaft 36 and this cam 39 engages and operates against the end of the lever 29. (See particularly Figure 4.) The end of the lever 28 is engaged and operated upon by another cam 40 on the shaft 36 and these cams are arranged with respect to each other so as to operate in timed relation upon the ends of the respective levers 27-28-29.

Thus it will be seen by rotation of the cam shaft 36 the respective levers and the position in which the cams are set with respect to each other determines the predetermined order or sequence in which the levers 27-28-29 operate upon the slide 19 to raise it.

The cam shaft is operated from a motor 41 by means of a belt 42 which passes over a pulley 43 on the motor shaft (see particularly Figure 3). The belt also passes over a pulley 44 loosely mounted upon the shaft 36 and connected to the pulley for rotation therewith is a gear 45 that in turn meshes with a gear 46 that is carried by a shaft 47 journaled in suitable bearings and extending parallel with the cam shaft 36.

Secured to the shaft 47 at the opposite side of the machine and for rotation therewith is a gear 48 which in turn meshes with a gear 49 that is secured to the cam shaft 36 for rotation therewith.

The platform 17 is provided with an opening 50 extended therethrough and removably seated in this recess is a die 51 which is open at its top and bottom and constitutes the compression chamber for the material.

Disposed below the top 52 of the slide 19 is a tubular member 53 which is provided with external screw threads and supported by this tubular member is a tubular extension 54 (see particularly Figure 7), the lower end of which is preferably reduced as at 55 and is provided with external screw threads 56 adapted to telescope into and engage internal threads in the end of the tubular member 53, to form an extension thereof. This tubular extension 54 constitutes one of the lower compression members and is adapted to be reciprocated within the die 51. The tubular member 53 together with the extension 54 is supported by means of nuts or collars 57-58 that are threaded upon the tubular member 53 and are spaced from each other in directions lengthwise of the axis of the member 53.

These collars or members 57-58 may be adjusted with respect to each other and upon the tubular member 53, for a purpose to be set forth, and are adapted to be held in their adjusted positions in any suitable manner, such as by means of a fastening member 59, one edge of which is adapted to enter recesses 60 in the periphery of each of the members 57-58, and the member 59 is held in position in any suitable manner such as by means of a fastening screw or bolt 61.

To adjust the members 57-58 the bolt 61 is released so that the member 59 may be moved out of the recesses in the periphery of the members 57-58, after which the latter may be turned upon the tubular member 53 and may be then locked in their adjusted position by repositioning the member 59.

The tubular member 53 with its extension 54 is supported by means of a lever 62, the end 63 of which latter projects into the space between the collars 57-58, the lever being supported for oscillatory motion by means of a sleeve 64 to which latter the lever or arm 62 is connected.

This lever 62 is oscillatable about its support by means of a cam 65 (see Figures 2 and 5) on the cam shaft 36 and which cam co-operates with a roller 66 carried by a bracket 67 secured to an upright bar or rod 68 that is mounted for vertical reciprocation upon one of the walls of the frame by means of bolts 69 passing through slots 70 in the bar or rod, and this bar or rod is connected to the sleeve 64 by means of a link 71 pivotally connected, as at 72, to the bar or rod, and at its other end as at 73 to an arm 74 extending from the sleeve 64.

A spring 75 is provided, one end of which is secured to the bar or rod 68, as at 76, and is anchored as at 77 to a fixed support and tends normally to move the bar or rod 68 in one direction and also to hold the roller 66 in a position that it will be engaged by the cam 65.

It will therefore be manifest that inasmuch as the end 63 of the lever 62 is positioned between the nuts or collars 57-58, the tubular member 53 with its extension 54 will be held in position and that according to the direction of operation of the lever the tubular member, or one of the lower compression members, will be correspondingly moved, the time in the cycle of operation of the lever 62 at which the lower compression member will be operated, being determined by the relative positions of the nuts or collars 57-58, and this arrangement of the nuts or collars with the end 63 of the lever 62 will also determine the period of dwell which the lower compression member 54 will have during the cycle of operation of the press.

A stationary core member 78 is mounted upon a fixed support 79 and is of a length that it projects entirely through the lower tubular compression member 54 and into the compression chamber in the die 51, terminating substantially flush with the top of the compression chamber 80 (see particularly Figures 7 and 9).

An outer tubular member 81 telescopes with the tubular member, or one of the lower compression members 54 and is supported by the top 52 of the slide 19, being held in position in any suitable manner such as by means of a collar 82 which is anchored to the top 52 of the slide 19 and overhangs a shoulder 83 on the member 81 so that the slide and the member 81 will be connected together for reciprocation in unison upon the operation of the slide.

The inner tubular member 54, however, is also

adapted for independent movement with respect to the outer tubular member 81 of the lower compression member.

A collar 84 loosely surrounds the compression member 81 and is adapted for movement upon the member 81 in directions lengthwise of the axis of the latter, and this movement is accomplished through the medium of a lever pivotally supported intermediate its ends, as at 85, upon a bracket 88 carried by the slide 19. The collar 82 is provided with an open circumferential groove 87 and the lever 88 is bifurcated so as to stand astride of the collar so that the extremity 89 of the lever will enter the groove 87 to raise and lower the collar upon the member 81 upon the reciprocation of the lever 88 about its pivot 85.

The other end 90 projects between two nuts or collars 91-92 adjustably mounted upon a rod or support 93, the latter being held in a fixed position in any suitable manner preferably by being disposed between and secured to the bottom of the platform 17 and the support 79.

By adjusting the nuts or collars 91-92 the time in the cycle of operation of the machine at which the collar 84 will be moved upon and with respect to the compression member 81 may be varied.

This collar 84 is provided as a means for moving the inner compression member or section 54 with respect to the outer section or compression member 81 and in order to effect this operation the collar 84 (see particularly Figures 7 and 9) is provided with a pin or projection 94 which extends inwardly through a slot 95 in the member 81 and is connected to the inner member or section 54 of the lower compression member so that when the slide 19 is raised, the two sections 54-81 of the lower compression member will be simultaneously moved in a fixed relation to each other. When, however, the end 90 of the lever 88 contacts the nut or collar 91 as the slide 19 is raised, it will be manifest that the lever 88 will be rocked about its pivot 85 and the inner section 54 of the lower compression member will be moved with respect to the outer section 81, as the end 90 of the lever will contact the nut or collar 91 at the time in the cycle of operation of the machine when the member 81 has reached the limit of its movement by the slide 19. This independent movement of the inner section 54 with respect to the outer member 81 of the lower compression member is for the purpose of insuring a uniform compression of the work being operated upon.

It has been found that in machines of this character the compression of the material from which the article is formed, and especially hollow articles having a flange or projection extending therefrom, has not been uniform with the result that the density of the material in the product has not been uniformly produced.

Therefore, with the present construction the outer portion of the product will be compressed by the outer section 81 of the lower compression member while the central portion of the product, which surrounds the aperture through the product, that is, the inner portion of the product will be uniformly compressed with the outer portion. Obviously similar compression elements are provided for the other side of the product and will be later described.

The material to be compressed is supplied from any suitable source in any suitable manner, preferably through a chute 96 at the end of which is provided a cap 97 having an open bottom and

this cap is pivotally mounted, as at 98 (see particularly Figure 2) upon the platform 17 so that the cap 97 may be swung into a position over the open top end of the compression chamber 80 and to be moved therefrom. This movement may be accomplished in any desired or suitable manner, such as by means of a lever 99 pivotally mounted intermediate its ends, as at 100 upon a suitable support. To the upper end of this lever 99 is connected a rod 102 one end of the rod being adjustably connected as at 103 with an ear or projection 104 on the cap or member 97 so that when the lever 99 is swung about its pivot 100, the cap 97 will be correspondingly moved about its pivot 98. If desired, a suitable spring 105 may be provided with tends normally to move the cap 97 in one direction.

The other end 106 of the lever 99 terminates adjacent the cam shaft 36 and at the end of the lever may be provided a roller 107 (see Figure 5). This roller 107 projects into and moves within a cam groove 108 preferably in the cam 37, and the bottom 109 of a portion of the cam groove is undulated so that as the cam is rotated and as the undulated surface 109 contacts the roller 107, it will impart a vibratory movement to the lever 99 and this in turn will impart a vibratory movement to the cap 97 so as to insure a uniform distribution of the material within the compression chamber 80.

After the chamber 80 has been supplied with material the cap or member 97 is swung about its pivot and will scrape off the surplus material during the movement of the cap in one direction.

If desired, a shield or guard 110 (see Figures 5 and 6) may be provided to project above the platform 17 so as to prevent dissipation of the material.

Arranged above the platform 17 is another slide 111 similar to the slide 19 and this slide 111 carries one of the upper compression members 112. This member 112 is tubular and is provided with a head 113 which rests upon the portion 114 of the slide 111 being held in position against the portion 114 and for rotation with respect thereto by means of a collar 115, a portion 116 of which latter engages over the head 113 and is secured in position by fastening screws 117. The tubular member is provided with external threads 118 at its free end and threaded thereupon is a nut or collar 119. Pivotally connected to the nut 119 and by one end thereof is a link 120, as at 121. The other end of the link is pivotally connected, as at 122, to one end of a lever 123 which latter is pivotally mounted intermediate its ends, as at 124. Pivotally connected to the other end of the lever 123, as at 125, is a bar or rod 126, the lower end of which terminates adjacent the cam shaft 36, and is provided with a yoke shaped portion 127 that stands astride of the cam shaft (see Figure 5). Carried by the arms of the yoke are rollers 128-129 and with which rollers a cam 130 co-operates, this cam 130 being secured to the cam shaft 36 for rotation therewith.

It will thus be seen that when the cam shaft is rotated the cam 130 co-operating with the rollers 128-129 will cause the lever 123 to be oscillated about its pivot and a reciprocatory movement will be imparted to the slide 111. Secured to this slide and depending therefrom is a tubular member 131 which constitutes the outer section of the upper compression member and is arranged in alignment with the compression chamber 80 so that upon the lowering of the slide 111 it will enter the compression chamber and will co-op-

erate with the lower compression element 81 to compress a portion of the material therebetween.

By the adjustment of the member 112 with respect to the nut 119, which may be accomplished by rotating the member 112 by means of a suitable tool or implement inserted in suitable apertures 132 in the member 112, the extent to which the end of the compression member 131 will enter the chamber 81 may be varied.

In order to hold the member 112 in position and against the portion 114 of the slide there may be provided a tubular bolt 133 which is threaded through a portion 134 of the slide 111. The lower end 135 of this tubular bolt 133 is preferably reduced so as to form a shoulder 136, the reduced portion 135 entering the end of the tubular member 112 so that the shoulder 136 will abut the extremity of the member 112. Adjustment of the bolt 133 may be had by means of an angular extremity 137 thereof which is adapted to receive a wrench or other adjusting tool.

It will therefore be seen that this element 133 will serve as a means for not only holding the element 112 in position but also will hold it against rotation.

Extending through the members 112 and 131 is a tubular element 138 which constitutes the inner section of the upper compression member. This element 138 also extends through the tubular bolt 133 thereby adapting the compression element 138 for movement with respect to the element 112. This independent movement of the element 138 with respect to the element 112 is preferably accomplished through the medium of a lever 139 pivotally supported intermediate its ends, at 140. A link 141 is pivotally connected at its end, as at 142 to one end of the lever and by its other end, as at 143, to a yoke 144. The end of the element 138 is threaded through the bottom of the yoke 144, as at 145, and a lock nut 146 may be provided if desired.

The lever 139 is rocked about its pivot 140 so as to reciprocate the inner upper compression member 138 by means of a bar or rod 147 pivotally connected at one end, as at 148, to the lever. The other end of the bar 147 terminates adjacent the cam shaft 36 (see particularly Figures 2 and 3) and carries a roller 149. This roller co-operates with a cam carried by the shaft 36. The bar or rod 147 is supported by means of a link 147a pivotally connected by one end to the bar 147 as at 147b (see also Figure 5) and at its other end, as at 147c to an arm 147d on the sleeve 64.

The cams which operate the slide and the inner compression tubular member 138 above the bed are so arranged to cause the tubular members 138 and 131 to move in unison for a portion of the operation of the machine and then while the tubular member 131 is maintained at rest the compression element or member 138 is moved with respect to the member 139.

The operation of the press is as follows:

The slide 19 is at its lowest point to provide a pocket or chamber for the material and the pocket or compression chamber is of a size to receive a volume of material greater than the volume contained in the finished product. The cap 97 is then moved to the position shown in Figure 7 so that the material will be supplied to the compression chamber 80. The cap 97 is agitated during this operation so as to equally distribute the material in the compression chamber. Before the cap 97 is removed, the slide 19 is raised by the lever 27, that is, by reason of the high portion of the cam 37 operating upon the end 38 of the lever

27 to raise the slide. While the chamber is being filled, the low portion of the cam 37 is engaging the end 38 of the lever 27 so that the slide 19, which has fallen by its own weight, will remain in the lowermost position. Before the cap 97 is moved out of position over the chamber, the high portion of the cam 37 will engage the end of the lever 28 and raise the slide so as to eject the surplus amount of material from the chamber back into the supply which is contained within the cap 97. The cap is then moved from over the compression chamber. The upper slide 111 is then lowered and when the chamber is closed by the element 31, the lower slide 19 is raised and compression will then take place between the upper and lower compression members.

Before the upper and lower compression members move away from each other and during the upward movement of the lower slide, and when the lower slide has reached the limit of its upward movement, the inner compression element 54 is given an extra movement with respect to the outer lower compression element 81 to compress the innermost portion of the work or the portion which surrounds the core 78 and is in close proximity thereto. This will insure a uniform compression throughout the entire area of the product. This additional movement of the element 54 with respect to the element 81 is caused by reason of the end 90 of the lever 89 contacting the upper nut or collar 91 on the bar or rod 93 as shown more clearly in Figure 9 of the drawings.

Similarly a movement of the upper inner tubular compression element 138 will be imparted thereto with respect to the element 131 through the medium of the lever 139 and the bar or rod 147 which is operated by the cam 150.

After the compression operations, the upper compression elements are raised while the lower compression elements 54-81 remain at rest and will so remain until the upper die moves far enough away from the top of the compression chamber to permit the work to be ejected from the compression chamber. The lower compression members will be operated by the lever 29 which raises the slide 19.

The ejection of the finished product from the compression chamber will be effected by the operation of the lever 28 which moves the slide 19 upwardly. After the article has been removed from the compression chamber the cams operate to permit the respective levers to move out of engagement with the respective abutments 23-24-25, thereby allowing the slide 19 to drop of its own weight or return to its lowermost position so that a new supply may be delivered into the compression chamber.

It will therefore be manifest that with this construction and operation there will be insured a uniform density throughout the area of the product.

Furthermore, with this improved machine an article, such as the article 151 shown in Figure 9, may be formed. That is, the article may be provided with a flange or extension 152-153 on opposite sides of the body 154 and at the same time the material which encompasses the opening will be subjected to the same degree of pressure as the body portion 154 which extends beyond the flanges 152-153. Furthermore, by the operation of the ejector mechanism, the article may be removed entirely from the compression chamber without the danger of injuring the product.

During the compression operation the compression elements have a dwell in their movement, thereby allowing the material to set while the same is being held under pressure.

It will also be manifest that with this improved construction all of the adjusting mechanism for the slide and for the compression elements are freely accessible and are located at one side of the machine, with the result that any adjustment or change in the extent of movement or in the order or sequence of operation of the various cams may be readily obtained without the necessity of dismantling the parts of the mechanism.

If desired, mechanism may be provided whereby a core may be inserted into the compression chamber 80 through the side thereof to produce an opening in the product transverse to the central opening.

In such event there may be provided a core 155 (see particularly Figure 10) which is connected to a slide 156 and this core is adapted to be inserted through a suitable opening 157 in the wall of the chamber 80.

The slide is suitably guided and is provided with an opening 158 therethrough, the walls 159 of which are inclined and the opening 158 is disposed above a suitable opening 160 in the platform 17.

Carried by the upper slide 111 is an operating member 161 which is preferably inclined and is arranged in register with the opening 158 in the slide 156 so that when the slide 111 is lowered to lower the upper compression member 131 into the chamber 80, the projection or member 161 will enter the opening 158 in the slide 156 and by reason of the inclined shape of the projection and the inclined walls 159 of the opening 158 the core 157, as the slide is lowered, will be moved into the chamber 80.

When the slide 111 is raised, the projection 161 will pass out of the opening 158 in the slide 156 and will cause the core 157 to be withdrawn from the chamber 80.

Should it be desired to impart an extra compression or squeezing movement to the inner upper compression element 138 mechanism similar to the mechanism for accomplishing such movement in the lower compression elements may be provided. To that end there may be provided a sleeve 162 which encompasses the element 131 and the sleeve is provided with an open circumferential recess 163. A lever 164 is pivotally supported intermediate its end as at 165 upon a bracket 166 which latter is carried by the slide 111.

The forward end 167 of the lever 164 projects into the recess 163 so as to slide the sleeve 162 upon the element 131 when the lever is rocked about its pivot. A pin similar to the pin 84 (Figure 9) is connected to the sleeve 162 and passes through a slot similar to the slot 85 which is shown in Figure 9, in the element 131, and is secured to the inner upper tubular compression member 138 so that upon movement of the sleeve 162 upon the element 131 the same result will be produced as that shown in Figure 9.

The lever 164 is rocked about its pivot 165 preferably by means of an abutment 168 which is adapted to engage a stop 169 mounted upon the platform 17. The abutment 168 is adjustably mounted in the end 170 of the lever 164 so as to control the time in the operation of the slide 111 at which the abutment 168 will engage the stop 169.

With this improved construction it will be manifest that after the material has been delivered into the compression chamber 80 and when the chamber is closed, and before the operation of the compression members upon the material to compress the same, the movement of the lower compression members with respect to the upper compression members will cause an equal distribution of the material in the compression chamber. That is, the material will be forced upwardly toward the upper compression members so as to provide sufficient material to form the flange 153 on the upper side of the body 151 (see Figure 9).

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. In a machine for compressing material into tablet form having a boss or projection of substantial length on both sides thereof providing a tablet having portions of varying thickness, a forming chamber, compression elements having sections movable relatively to one another, means for moving said elements in said chamber toward each other to effect compression, and away from each other, means for delivering into said chamber and between said compression elements material in excess of the volume of material contained in the finished product, means for causing one of said elements to eject the material before compression thereof, additional means for further actuating a section of one of said elements to exert an additional pressure upon the tablet to further compress it in the zone of its greatest thickness, after the compression elements have reached the limit of their initial compression movement in said zone and while the remaining portion of the tablet is maintained under a constant and unyielding pressure.

2. In a machine for compressing material into tablet form having a boss or projection of substantial length on both sides thereof, a forming chamber, compression elements movable in said chamber in directions towards and away from each other, operating means for said elements, means for delivering into said chamber and between said compression elements material in excess of the volume of material contained in the finished product, means for ejecting the excess material before compression of material, and means for exerting an additional pressure upon the tablet in the zone of its greatest thickness after the compression elements have reached the limit of their initial compression movement in said zone and while a constant and unyielding pressure is maintained upon the remaining portion of the tablet, the last recited means embodying a portion of one of said compression elements, and means in addition to the first said operating means for said element, operating upon said portion of said element.

3. In a machine for compressing material into tablet form having a boss or projection of substantial length on both sides thereof, a forming chamber, compression elements movable in said chamber in directions towards and away from each other, actuating means for said elements, means for delivering into said chamber and between said compression elements material in ex-

cess of the volume of material contained in the finished product, means for ejecting the excess material before compression of material, and means for exerting an additional pressure upon the tablet in the zone of its greatest thickness after the compression elements have reached the limit of their initial compression movement in said zone and while a constant and unyielding pressure is maintained upon the remaining portion of the tablet, the last recited means embodying a portion only of each of said compression elements and means individual to said portions for moving them relatively to the remaining portion of said elements after said elements have reached the limit of their movements by the respective first said actuating means therefor.

4. In a machine for compressing material into tablet form, a forming chamber, compression elements movable in said chamber in directions toward and away from each other, means for delivering into the chamber and between said compression elements a surplus of the material to be compressed, means for actuating one of said compression elements, a slide carrying the other of said compression elements, a plurality of actuating means for successively and separately operating said slide to respectively eject the surplus material from the chamber, compress the material in the chamber and eject the finished product from the chamber, driving means for operating the said slide actuating means, one of said compression elements being of sectional construction, and positive means operating automatically as the last said compression element reaches the limit of its movement in one direction by the movement of the slide by its aforesaid actuating means for imparting a further compression movement to one of the said sections of said compression element.

5. In a machine for compressing material into tablet form, a forming chamber, compression elements movable in said chamber in directions toward and away from each other, means for delivering into the chamber and between said compression elements a surplus of the material to be compressed, means for actuating one of said compression elements, a slide carrying the other of said compression elements, a plurality of actuating means for successively and separately operating said slide to respectively eject the surplus material from the chamber, compress the material in the chamber and eject the finished product from the chamber, a drive shaft common to all of said slide actuating means, the said compression element which is carried by the slide being of sectional construction, means operating automatically as the last said compression element reaches the limit of its movement in one direction by the movement of the slide by its aforesaid actuating means for imparting a further compression movement to one of the said sections of said compression element, and means separate from the actuating means for the other of the said compression elements for imparting a further and squeezing movement thereto when it has reached the limit of its movement by the first said actuating means therefor.

6. In a machine for compressing material into tablet form, a forming chamber, compression elements movable in said chamber in directions towards and away from each other, means for supplying to the chamber and between said elements, the material to be compressed, means for actuating one of said elements, the other of said compression elements being of sectional

construction, positive means individual to said sections for actuating them in unison and in fixed relation to each other, and means individual to said actuating means for moving one of said sections with relation to the other after the said sections have reached the limit of their movement in unison and in the same direction as the last said movement.

7. In a machine for compressing material into tablet form, a forming chamber, compression elements movable in said chamber in directions towards and away from each other, means for supplying to the chamber and between said elements a volume of material greater than the volume contained in the finished product, means for actuating one of said elements, the other of said compression elements being of sectional construction, positive means individual to said sections for actuating them in unison and in fixed relation to each other, to eject the surplus material and also for compressing the material in the chamber, and means individual to said actuating means for moving one of said sections with relation to the other after the said sections have reached the limit of their movement in unison and in the same direction as the last said movement.

8. In a machine for compressing material into tablet form, a forming chamber, compression means embodying a main compression element and a supplemental compression element, both movable in said chamber to initially compress the material, said supplemental element being further operable to compress a portion only of said material, means for operating said elements for such initial pressure, and means for actuating said supplemental element to impart to a portion of the material in said chamber a further compression after both of said compression elements have reached the limit of their compression movement, while maintaining a constant and unyielding pressure upon the material by said main compression element and within a predetermined zone.

45. 9. A machine for compressing material into form-sustaining shape, embodying a chamber comprising elements reciprocable in the chamber in directions towards and away from each other, means individual to the elements for respectively reciprocating them for compressing material therebetween, one of said elements being constructed of relatively movable sections, both of said sections being movable in unison and simultaneously operating upon the material to initially compress the entire material in zones individual to the sections, and means individual to one of said sections for positively operating it with respect to the other section to further compress the material in its respective zone, 60 after the said other section has reached the limit of its compression movement.

10. A machine for compressing material into form-sustaining shape, embodying a chamber comprising elements reciprocable in the chamber in directions towards and away from each other, means individual to the elements for respectively reciprocating them for compressing material therebetween, one of said elements being constructed of relatively movable sections, both of said sections being movable in unison and simultaneously operating upon the material to initially compress the entire material in zones individual to the sections, means individual to one of said sections for positively operating it with respect to the other section to further com-

press the material in its respective zone, after the said other section has reached the limit of its compression movement, and a core extending into said chamber and encompassed by both of said sections.

11. A machine for compressing material into form-sustaining shape, embodying a chamber comprising elements reciprocable in the chamber in directions towards and away from each other, means individual to the elements for respectively reciprocating them for compressing material therebetween, both of said elements being constructed of relatively movable sections, both of

5 said sections of both of said elements being movable in unison and simultaneously operating upon the material to initially compress the entire material in zones individual to the sections, and means individual to one of said sections of each of said elements for positively operating it with relation to the other respective section to further compress the material in its respective zone, after the said other section of the respective elements has reached the limit of its compression movement.

ALBERT S. KUX.
